UNITED STATES PATENT OFFICE.

RALPH HOWARD PETTENGILL, OF HAVERHILL, MASSACHUSETTS.

WOOD-HEEL-TURNING MACHINE.

Application filed May 5, 1928. Serial No. 275,344.

This invention relates to that type of wood heel turning machines, or machines which form the back and sides of wood heels, on which the heel blank is mounted on a holder 5 and is moved into operative relation successively, with a pair of oppositely rotating cutters, the blank being shaped on one side from the breast to the middle of the back, by one cutter and then being shaped in like manner 10 on the opposite side by the other cutter.

In performing this operation the shape of the side surfaces formed on the blank are determined by the shape of the cutter knives, and by the movement of the holder relative 15 thereto, as the operation is being performed, the holder having a combined horizontal swinging and vertical tilting movement, and in some instances a bodily vertical movement, and the present invention particularly relates to the means for controlling the vertical 20 swinging movements of the holder.

The construction which is used in this connection almost universally comprises a U-form track on which the holder is supported 25 at its outer end, the means for supporting the track being vertically adjustable and the track being held at different inclinations relative thereto. To vary the inclination of the track and thereby vary the inclination or 30 pitch of the back of the heel, the track has been pivotally mounted at its ends on the vertically adjustable support on which it is mounted (as disclosed in Patent No. 1,247, 35 335), the pivots on which the track is mounted being located beneath the track in proximity to the vertical plane of the axes of the cutters. With this arrangement the extent to which any portion of the track is moved vertically when it is adjusted increases from a minimum at its ends to a maximum at the middle thereof. In consequence 40 the inclination of the back of the heel which is formed decreases from a maximum at this point to a minimum at the breast edge. With 45 this arrangement, any variation of the inclination of the track varies its elevation to some extent at all points therein which support the jack. In making the necessary adjustments with this arrangement, to secure a desired pitch at the back of a heel, the bracket, or support on which the track is mounted, is first adjusted vertically, so that, when the 50 holder is swung to either side, the desired formation of the front portion of the sides

of the heel, or portions adjacent the breast 55 will be secured. If then the inclination of the track is varied to secure the desired pitch at the back, the result will be that the adjustment for the front portion of the sides will be disturbed to such an extent that further 60 vertical adjustment of the support will be necessary to compensate for the second adjustment. In consequence a series of adjustments, first of the elevation of the track and then of its inclination must usually be made 65 before approximately the formation desired at all points is secured.

The object of my invention is to provide a form of adjustment in the connection above referred to, whereby a single adjustment may be made with relation to a cutter of predetermined configuration to secure the desired formation at the side of the heel adjacent the breast, and then a further adjustment may be made to secure the desired pitch at the 75 middle of the back without disturbing, or in any way affecting the adjustment which has previously been made.

I accomplish this object primarily by so mounting the track which controls the inclination of the blank holder with relation to the vertical, that adjustment thereof to vary the pitch of the heel at the back will be about an axis which intersects the points of contact of the jack with the track when in the 85 opposite side positions to which it is moved to form the side surfaces adjacent the breast.

For a more complete disclosure of my invention, and the particular means which I preferably employ in this connection, reference is now made to the following specification in connection with the accompanying drawings, in which:—

Fig. 1 is a front elevation of a wood heel turning machine containing an embodiment 95 of my invention.

Fig. 2 is a plan view and

Fig. 3 is a side elevation thereof.

Fig. 4 is a detail side view of the upper track.

Fig. 5 is a sectional view, on an enlarged scale, at line 5—5 of Fig. 4.

Fig. 6 is a detail perspective view of one of the pivotal supports for the tracks.

Fig. 7 is a plan view of one member of the 105 support and

Fig. 8 is a sectional view of the other member thereof.

In the drawings a common type of wood heel turning machine is illustrated, comprising a frame 10, in which a pair of cutter shafts 11 are mounted to rotate about vertical axes, said shafts having cutter knives 12 of suitable formation mounted thereon at their upper ends. A vertical pivot shaft 13 is mounted midway of the cutter shafts and a bracket 14 is supported thereby to swing horizontally. A vertical shaft 15 is rotatably and slidably mounted in the end of said bracket and the jack or heel holder 16 is pivotally mounted to swing vertically on the upper end of said shaft 15. A horizontally disposed, U-shaped lower track 17 is supported on a vertically adjustable bracket 18 mounted on the frame and an arm 19 on shaft 15 rests thereon to support said shaft 15 in all positions of the jack. A vertically adjustable bracket 20 is also mounted on the frame 10 and a U-shaped upper track 22 is supported on said bracket in a manner to be specifically described.

The jack 16 is provided with a shoe 24 on its under side, said shoe extending longitudinally of the jack in position to rest crosswise of the track 22, to support the jack thereon. The lower edge of the shoe and the upper edge of the track are rounded transversely as shown in Figs. 4 and 5, so that the oppositely rounded surfaces provide practically a single point of contact. The jack is provided with the usual guide cam 25, which is arranged to engage a fixed guard 26 adjacent each cutter head. said cam corresponding in shape to the outline of the base surface of the heel blank to be turned, so that, when the jack is swung to either the full or dotted line position of Fig. 2, in which one side portion, or the other of the cam 25 is engaged with one of the guards 26, one of the cutters will be engaging the blank on the jack at one side near the breast surface, or approximately midway between the breast and the middle of the side, at which point the formation desired under practically all conditions may be secured without varying the inclination of the track 22. When the jack is in this position the shoe 24 rests on the track 22 at a certain point, which is indicated by point X in Fig. 4, the point X on each end portion of the track being located in the straight line x—x' of Fig. 2.

The operation of the machine, as thus far described, is the same as with all other machines of this type, the cutters being rotated oppositely, as indicated by the arrows in Fig. 2, and the holder being successively swung from the initial positions at the right and at the left of the cutters indicated by lines y and y' in Fig. 2 to the middle positions indicated by lines z—z' in Fig. 2, to shape each side of the blank from the breast to the middle of the back.

According to my invention, in mounting

the track 22 on the bracket 20, I provide a pair of rocker beds 28 which are mounted on bracket 20 directly beneath the opposite end portions of track 22, said beds each having a recess 29 in its upper side the bottom of which is concave and curved on a radius, when the parts are in position, having its center at the point X. A rocker 30 is secured on the under side of each end portion of track 22, and has a convex under face which fits the bottom of recess 29, so that a pivotal support is provided for each end portion of track 22, which has its axis coincident with the line x—x' connecting the points X on the top of the opposite end portions of the track. Each rocker bed 28 has a vertically projecting portion 31 at the outer side thereof, the inner side of each projecting portion being under-cut to form a groove 32, the bottom of which is continuous with the bottom of recess 29 and the top side of which is formed concentrically therewith and the rockers 30 are each provided with a flange 33 at the outer sides thereof, the bottom of each flange being continuous with the under side of the rocker and the top side thereof being formed concentrically therewith and adapted to be fitted into the groove 32 corresponding thereto, as shown in Fig. 6. With this arrangement the track 22 is pivotally mounted on the bracket 20 to tilt about the axial line x—x' thru the points X, and is securely held against lateral or vertical movement.

Suitable means for supporting and vertically adjusting the track 22 about the axial line x—x' are provided, the construction shown comprising a rod 35, which is pivotally connected to said middle portion of the track and a clamp 36 which is pivotally connected to the bracket 20 and in which rod 35 is slideable, the construction permitting the rod to be secured in any position therein, so that, to adjust the inclination of the track 22, the rod 35 is moved longitudinally in the clamp 36, causing the track to be tilted about the axial line thru points X and when the desired inclination is secured, the rod will be locked by the clamp securely holding the track in the position to which it is adjusted.

With the above described construction, in adjusting the apparatus to produce a heel blank having a certain formation at its sides and back, after the cutter knives, having suitably shaped cutting edges, have been secured to the cutter heads, the bracket 20 will be vertically adjusted to a position in which the desired formation of the front portion of the sides of the blank is secured, when the jack is held in the full or dotted line position of Fig. 2, in which position the shoe 24 of the jack will be resting on the track 22 at the point X, or in close proximity thereto, to which position, in making the cut at either side, the jack will have been advanced from

the extreme position, indicated by dotted lines y, y' in Fig. 2. The inclination of the track is then adjusted to secure the desired pitch at the middle of the back of the heel, 5 and this adjustment in no way disturbs the adjustment previously made for the formation when the jack is in the side position over the point X. The correct adjustment to secure the production of a heel blank of certain 10 formation may thus be quickly secured by making two adjustments, readjustment at one point to compensate for adjustment at another point thus being unnecessary.

I claim:

1. In a wood heel turning machine a cutter mounted to rotate about a vertical axis, a heel blank holder mounted to swing horizontally and tilt vertically, to hold the blank in operative relation with the cutter and successively form the opposite sides thereof, and a track extending oppositely from a point in front of the cutter to points at opposite sides thereof in position to support said holder and to tilt it vertically as it is moved horizontally, said track being pivotally mounted at points adjacent the opposite sides of the cutter to tilt about an axis extending approximately thru the points of engagement of the holder with the track 25 when in positions to form the side portions of the heel adjacent the breast thereof.

2. In a wood heel turning machine, a cutter mounted to rotate about a vertical axis, a heel blank holder mounted to be swung horizontally about the cutter and to be tilted vertically to and from the same, to hold the blank in positions successively to form the opposite sides of the heel, and a U-form track having its ends disposed at the same elevation 30 at opposite sides of the cutter and its intermediate portion disposed in front thereof to provide a rest for supporting the holder and controlling its tilting movements, said track being supported for adjustment about 35 a horizontal axis arranged to permit adjustment thereof without varying the position of the holder when the latter is held in a position to permit operation of the cutter on the blank at either side thereof adjacent its breast face and to vary the position to which it is tilted at other points.

3. In a wood heel turning machine, a pair of cutters mounted to rotate about vertical axes, a heel blank holder mounted at its inner end between said cutters to be swung horizontally and tilted vertically in operative relation with said cutters, successively to form the opposite sides of the heel from breast to back as the holder is moved from initial positions at the right and the left of the cutters to a position in front thereof, a horizontally disposed track arranged to support said holder at its outer end, to control its tilting movements and to extend from a 65 point in front of the cutter to the right and

to the left thereof, and a vertically adjustable support for said track having a pivotal connection therewith arranged to permit variation of the inclination of the track about an axial line, so located that adjustment 70 thereof does not substantially affect the position of the holder when the latter is held in a position adjacent each initial position thereof.

4. In a wood heel turning machine, a pair 75 of cutters mounted to rotate about vertical axes, a heel blank holder mounted at its inner end between said cutter to be swung horizontally and tilted vertically in operative relation with said cutters successively to form 80 the opposite sides of the heel from breast to back, as the holder is moved from initial positions at the right and the left of the cutters to a position in front thereof, a horizontally disposed track arranged to support 85 said holder at its outer end, to control its tilting movements and to extend from a point in front of the cutter to the right and to the left thereof and a vertically adjustable support for said track, having a pivotal connection therewith arranged to permit variation of the inclination of the track about 90 an axial line, which intersects correspondingly opposite points in the track which support the holder during an initial portion of 95 each operative movement thereof.

5. In a wood heel turning machine comprising a cutter mounted to rotate about a vertical axis, a heel blank holder mounted to swing horizontally and vertically relatively to the 100 cutter, a horizontally disposed U-shaped track having its end portions at opposite sides of the cutter and its middle portion extending in front thereof, for controlling the vertical swinging movements of the holder, an arm 105 extending downwardly from each end portion of the track, each having a convex-bearing face at its lower end formed about an axial line which intersects correspondingly opposite points in the end portions of the track 110 surface, a support having bearing recesses correspondingly shaped and arranged to receive said convex faces, to permit vertical adjustment of the track about said line as a center and means for holding the track in its 115 different positions of adjustment about said axial line.

6. In a wood heel turning machine comprising a cutter mounted to rotate about a vertical axis, a heel blank holder mounted 120 to swing horizontally and vertically relatively to the cutter, a horizontally disposed U-shaped track having its end portions at opposite sides of the cutter and its middle portion extending in front thereof for controlling the vertical swinging movements of the holder, an arm extending downwardly from each end portion of the track, a segmental flange projecting in opposite relation 125 from one side of each arm, each flange being 130

concentrically formed on its top and bottom sides with relation to an axial line which intersects correspondingly opposite points in the end portions of the track surface, a support having correspondingly formed segmental slots in which said flanges are located, to permit the track to be swung vertically

about said axial line, and means for holding the track in its different position of adjustment about said axial line

10

In testimony whereof, I have signed my name to this specification.

RALPH HOWARD PETTENGILL.
